UNITED STATES PATENT OFFICE.

CARL SCHWARZ, OF CHARLOTTENBURG, NEAR BERLIN, GERMANY, ASSIGNOR TO WESTINGHOUSE ELECTRIC & MANUFACTURING COMPANY, A CORPORATION OF PENNSYLVANIA.

RELAY ARRANGEMENT FOR CHANGING THE TUNING OF WIRELESS APPARATUS.

Application filed October 31, 1921. Serial No. 511,828.

To all whom it may concern:

Be it known that I, CARL SCHWARZ, residing at Charlottenburg, near Berlin, Germany, have invented certain new and useful 5 Improvements in Relay Arrangements for Changing the Tuning of Wireless Apparatus, of which the following is a specification.

This invention relates to radio signaling apparatus of the type shown in my co-pending 10 applications Ser. No. 511,832, filed Oct. 31, 1921, and Ser. No. 511,827, filed Oct. 31, 1921. Radio signaling apparatus of this type has provision for changing the wave length by the operation of a switching device. 15 It is an object of the present invention to provide for changing the tuning of the signal-sending device without changing the tuning of the sending antenna so that the sending system will thereby be prevented 20 from radiating signals.

Other objects of the invention and specific details of the construction will be apparent from the following description and the accompanying drawing, in which—

25 The single figure is a diagram showing the apparatus and system of connections used.

The sending device includes an antenna system T_s . This may be any usual form of 30 sending antenna, such as an antenna and a ground connection. The antenna circuit includes a coil L_s which is connected to a switch regulated by the relay R_s . In the illustrated position of this switch, the whole 35 of the coil L_s is included in the antenna circuit. When the relay R_s moves the switch to the opposite position, a portion only of the coil L_s is thus included. The sending apparatus S associated with the antenna system T_s includes a vacuum-tube oscillation 40 generator V_s . Associated with this generator is an oscillating circuit including a coil L_g which is controlled by the relay R_g . In the illustrated position, the whole of the coil 45 L_g is included in the oscillating circuit. In the opposite position of the relay, a portion only of this coil is thus included.

The receiving instrument E is connected to 50 the antennae T_e which may be any form of antenna system, as explained in connection with the sending device. The receiving instrument includes a vacuum tube V_e and is coupled to the antenna circuit. A condenser C_k is connected in parallel to a

coil in the antenna circuit, and the condenser K_k is similarly connected in an oscillating circuit. These condensers are thus connected when the switch controlled by the relay R_e is in the illustrated position. In the opposite position of the switch, a condenser C_g 60 is connected in the antenna circuit in the place of the condenser C_k , and a condenser K_g is connected in the oscillating circuit in place of the condenser K_k .

It will thus be apparent that the several 65 switches can be so shifted by their associated relays as to change the sending and receiving systems from one wave length to another; and the device is, therefore, adapted 70 for use in any system of signaling among a plurality of stations where such changes are relied upon for enabling each station to correctly atune itself to the station with which it is to communicate.

The relays R_g , R_s and R_e are controlled 75 by a common circuit which is opened and closed by the switch u . This switch may be actuated by the selective station-calling device or by the switch hook, which is moved when the receiver is lifted. As explained in 80 the above mentioned copending application Ser. No. 511,827, one or the other way of controlling the switch will be used according as the change in tuning is to be made at the calling or the called station.

It is sometimes desirable, for adapting the 85 illustrated station to particular circumstances, to tune it to receive signals sent out by some other station and, at the same time, render its sending device inoperative, in 90 order that there shall be no danger of the operator at the illustrated station interfering with the signals while listening to a distant station. This is accomplished by means of the extra switch z which may be a telegraph 95 key or any other desired form of manually operated switch. With the apparatus in the illustrated position, that is, with the switch u open, if the key z is moved, the relay R_g will be energized, while the relays R_s and R_e remain deenergized. This will 100 result in tuning the oscillating circuit in the sending system to a different wave length from the radiating system of the sending device. Consequently, the oscillations generated will not be sent out and the station cannot, therefore, interfere with the signals coming from the distant station. This is par-

ticularly useful when the sending device has a tendency to cause noises in the receiving device at the same station.

If the switch u be closed, either by lifting 5 the receiver or by manipulating the calling device, the key z may be opened to cause the relay Rg to be deenergized while the relays Rs and Re are energized. Under these circumstances again, the oscillating circuit in 10 the sending device will be differently tuned from the radiating circuit in that device and, consequently, no signals will be sent and the action of the sending device at the illustrated 15 station will produce no noises in the telephone.

Many variations in the details of construction will occur to those skilled in the art and many different situations in which this invention can be used, without departing from 20 the spirit thereof, will at once be apparent, I, therefore, do not intend to limit it except as necessitated by the prior art or indicated in the claims.

I claim as my invention:

25 1. In a radio signaling system, means for changing the tuning, relays for controlling said means and a device for controlling one of said relays independently of the others.

2. In a radio signaling system, a sending device and a receiving device, means for controlling the tuning of each of said devices, 30 relays for actuating said means and means for operating one of said relays independently of the others.

3. In a radio signaling system, a sending 35 device and a receiving device, means for controlling the tuning of each of said devices, relays for actuating said means, a circuit and a circuit closing device for simultaneously operating all of said relays and a 40 supplemental circuit-controlling device for causing one of said relays to operate independently of the others.

4. In a radio sending system, a radiating 45 circuit, an oscillating circuit, switching means for changing the tuning of each of said circuits, a pair of relays for operating said switching means, and a device for operating the relay associated with the oscillating circuit independently of the other relay whereby the tuning of the oscillating circuit and the radiating circuit may be made to differ 50 from each other when desired.

In testimony whereof I affix my signature.

CARL SCHWARZ.
